UNITED STATES PATENT OFFICE.

WILLIAM H. ISLEY, OF JERSEY CITY, NEW JERSEY, ASSIGNOR OF ONE-HALF
TO FREDERICK A. HOELAND, OF SAME PLACE.

AWNING.

SPECIFICATION forming part of Letters Patent No. 284,741, dated September 11, 1883.

Application filed July 31, 1883. (No model.)

To all whom it may concern:

Be it known that I, WILLIAM H. ISLEY, of Jersey City, in the county of Hudson and State of New Jersey, have invented certain Improvements in Awnings, of which the following is a specification.

This invention relates to awnings for storefronts and similar use; and the invention consists in certain details of construction and combinations of devices, as hereinafter more fully set forth.

Figure 1 is a perspective view, showing the awning extended for use. Fig. 2 is a longitudinal section on the line *x x* of Fig. 1; Fig. 15 3, a longitudinal section of the roller, and Fig. 4 a plan view of devices for extending and retracting the awning.

To construct an awning on my plan, I provide an extensible frame consisting of two lazy-tongs, *B*, one at each side, which are connected at their upper edges by a series of transverse rods or bars, *e*, as shown in Fig. 2 and by dotted lines in Fig. 1, the ends of these rods *e* forming the journals for the joints at those 20 points, as shown in Fig. 2. The lazy-tongs will be made of light flat bars, and the cross-rods *e* may be made of gas-pipe; or they may be wooden bars, having metallic pieces attached to their ends to form the journals, in order to 25 render the frame as light as possible. The object of these cross-bars is to unite the lazy-tongs or extensible frames at each side, thus holding them in place and rendering the frame more rigid and less liable to be swayed or 30 moved about by the wind, and also to support the awning. Each pair of the lazy-tongs *B* is pivoted to a bracket, *c*, secured rigidly to the building, as shown in Figs. 1 and 2, while the inner end of the corresponding arm, *b*, is provided with a roller, *a*, which works in a groove 35 in a plate, *C*, secured to the wall of the building *A*, as shown. In the drawings I have shown this groove or track for the roller as being formed by two projecting ribs; but it may be formed by a depression or groove in the plate, if preferred, the object being to guide the arm *b* in a vertical line and prevent it 40 from being moved or displaced laterally. This guide, in connection with the cross-rods *e*, ena-

bles the frame to be made very light, and still 50 have the requisite strength and rigidity, and also enables it to be extended and retracted without binding or difficulty.

In order to operate the frame, I connect a bar or rod, *D*, with the cross-rod *e* nearest the 55 building, and extend it through the wall, if desired, its opposite end being pivoted to a lever, *L*, as shown in Fig. 2, so that by operating said lever the frame may be extended or retracted at will. This lever, with its rod *D*, 60 owing to the peculiar construction of the frame, as hereinbefore described, may be located at either side of the door, or even at either extreme side of the frame, and still be made to operate it perfectly. Instead of arranging the 65 lever vertically, as shown in Fig. 2, it may be arranged horizontally, as shown in Fig. 4, and be pivoted to the ceiling in the recess over the door in case there be such recess on the outside, or, if not, then inside of the building, and 70 be operated by cords *h*, attached to its opposite ends, said cords passing over pulleys *t*, as shown, and thence down behind the doors, where they will be out of the way and still be accessible. In some cases it may be desirable, 75 on account of the internal arrangement of the room, to attach both cords *h* to one end of the lever *L*, in which case the two pulleys *t* will be arranged on opposite sides of that end of the lever, so that by pulling on one cord the 80 frame will be extended, and by pulling on the other it will be folded or retracted, the arrangement of the cords and pulleys of course being varied as may be necessary to adapt them to the circumstances of each particular case, and 85 which can readily be done by any person accustomed to putting up awnings.

The covering or canvas *H* will be prepared in the usual manner, it being secured to the outer cross-bar, *e*, and its inner end being secured to a roller, *I*, journaled in brackets *d* just above the brackets *c*, as shown in Figs. 1 and 2. This roller I should either be provided with a spring to cause it to rotate similar to the spring curtain-rollers in general use, as 90 indicated in Fig. 3, so as to automatically wind the canvas *H* upon the roller *I* when the frame is retracted, or it may be provided with a 95

weight, n , for that purpose, as may be preferred. In Fig. 2 I have shown the weight n as being located within the building and connected by a cord, f , to the roller I, said cord 5 passing over a pulley, l , and thence through the wall, the weight n preferably being inclosed in a box or casing, as shown. I prefer to use a weight, because the power which it will exert upon the roller will be uniform, 10 whereas the spring will be constantly varying in its tension as the frame with the canvas is extended or retracted. The spring or weight should be adjusted so as to exert only such force as may be necessary to wind up the canvas, as whatever excess of force there might be would have to be overcome in extending the frame, and would also tend to retract the frame. While I have represented the weight n as being located within the building, it is obvious 15 that it may be arranged on the outside, if desired, and, in cases where there is an area or vault for it to pass down into, it may be desirable to so arrange it, that being a matter of choice or convenience merely.

25 In order to protect the canvas H from the weather, I place a cover, E , over the roll, as shown in Fig. 2, wherein it is represented as being made of a strip of sheet metal of suitable width, and so curved as to fit over the roller I, with its inner edge secured to the building, there being just space enough below 30 its outer edge to permit the canvas to pass under it without contact; or, if preferred, the cornice along the front of the building at that point may be constructed to form a cover or protection. This curved cover is specially adapted to be applied to buildings already erected to which the awning is to be applied, and where no provision has previously been 35 made for it.

40 By this construction and arrangement of the

various parts and devices I am enabled to produce an awning that operates successfully, and that can be extended or retracted either from without or within the building, and in which the awning, when not in use, is thoroughly protected from the weather.

45 It is obvious that, if desired, a cord, r , may be arranged on the outside, as shown in Fig. 2, by which the roller I can be rotated, and by 50 winding up the canvas be made to fold up the frame at the same time. This plan will be used in those cases where for any reason it is not convenient or desirable to use the lever, or to have any of the parts extended within the 55 building, as may sometimes be the case.

Having thus fully described my invention, what I claim is—

1. An extensible frame for awnings, consisting of two or more lazy-tongs, B , connected by 60 a series of cross bars or rods, e , arranged intermediate between the inner and outer ends of the lazy-tongs, substantially as described.
2. In an awning-frame, the lazy-tongs B , having the free end of their inner arms, b , provided with a roller, a , in combination with the plates C , arranged to operate substantially as set forth.
3. In combination with an extensible awning-frame constructed as described, the rod D 70 and lever L for operating the same, as set forth.
4. In combination with the extensible frame and lever L for operating the same, the roller I, provided with the internal spring and the 75 canvas H , all arranged to operate substantially as shown and described.

WILLIAM H. ISLEY.
